(57) **CLAIM**

The ornamental design for a bathing tub, as shown and described.

DESCRIPTION

In a preferred embodiment, the nature of this product is as a plumbing fixture in the form of a bathing tub primary useful for washing the human body.

FIG. 1 is a left, top, front perspective view of a bathing tub embodying my new design;

FIG. 2 is a top plan view thereof;

FIG. 3 is a front elevational view thereof;

FIG. 4 is a left side elevational view thereof;

FIG. 5 is a right side elevational view thereof;

FIG. 6 is a rear elevational view thereof;

FIG. 7 is a bottom plan view thereof; and,

FIG. 8 is a right, top, front perspective view of a bathing tub according to another embodiment of my new design having views that are mirror images of FIGS. 2-7.

The broken line representations of a drain and holes in the figures are for the purpose of illustration only, and form no part of the claimed design.
